UNITED STATES PATENT OFFICE.

JULIUS F. ADAMS, OF PITTSBURGH, PENNSYLVANIA; ANNA ADAMS LAUER ADMINISTRATRIX OF SAID JULIUS F. ADAMS, DECEASED.

RADIANT ELECTRIC HEATER.

Application filed September 21, 1923. Serial No. 663,951.

My invention relates to electric heating devices and particularly to radiant electric air heaters.

Among the objects of my invention are the following:—

To provide a relatively simple and compact radiant electric heater that shall embody a plurality of built-up heating elements that shall be easily and quickly removable from 10 the casing supporting the same.

To provide a radiant heater whose heating elements shall severally comprise a plurality of relatively simple and small refractory resistor-supporting members mounted on a lining and supporting means.

To provide a radiant electric heater whose heating elements shall comprise resistor-supporting members of ornamental appearance and of relatively low heat-storage capacity.

20 To provide a radiant electric heater having a plurality of extended heated elements and a plurality of means for selectively controlling the energization of the heating elements.

To provide a radiant electric heater having 25 a plurality of control switches mounted on a front panel of the heater and removable therewith.

In practicing my invention I provide an ornamental metal casing having an opening 30 in the front portion thereof and a removable rear wall panel. A refractory plate member interlocked with the casing is located in the front opening and carries a plurality of extended electric heating elements located in 35 side-by-side relation thereon. Each heating element consists of a plurality of relatively narrow, elongated, refractory resistor-supporting members, each having a plurality of openings extending laterally therethrough 40 and mounted on a pair of spaced metal rods which are, in turn, supported by the refractory plate. A resistor member wound in the form of an open helix, extends through the aligned openings in the refractory members 45 back and forth of the assembled group thereof.

A plurality of control switches is mounted 50 on a front panel of the casing which is easily and quickly removable therefrom, thereby permitting of easy access to the terminals of the heating elements and to a leading-in conduit for the supply circuit conductors, whose ends are connected to a pair of termi-

nal members mounted on a plate of insulating material secured to the inside of the back 55 panel.

In the drawings,

Figure 1 is a view, in front elevation, of a radiant air heater embodying my invention,

Fig. 2 is a top plan view of a removable 60 front panel and control switch aggregate comprising a part of the device embodying my invention,

Fig. 3 is a view, in vertical section, of the heater illustrated in Fig. 1, taken on the line 65 III—III thereof,

Fig. 4 is a partial view, in front elevation, of a plurality of interlocked heating elements,

Fig. 5 is a view, in front elevation, of a 70 refractory resistor-supporting bar,

Fig. 6 is a view, in side elevation thereof, and

Fig. 7 is a view thereof, in lateral section thereof, taken on the line VII—VII of Fig. 5. 75

An ornamental casing 11 is built up of suitable castings as illustrated in Figs. 1 and 3 of the drawing to comprise side portions 12 and 13, and a top portion 14.

A plurality of front supporting members 80 15 may be either integral with the side portions 12 and 13, or they may be suitably secured thereto. A plurality of rear supporting members 16 are provided and may be suitably secured against a bottom panel 17 and aid in 85 holding a removable rear sheet metal panel 18 in its proper operative position as a part of the assembled casing.

The casing 11 is provided with a front opening 19 within which is located a dished 90 refractory plate or member 21. The upper top and front portion of the member 21 is provided with an indentation or notch 22 extending across the top face in order that it may be interlocked with an integral web 95 or flange 23 of the casing 11. This locates the member 21 relatively to the top of the casing 11 and also holds it in its proper operative position within the casing.

A plurality of extended heating elements 100 24 are located in side-by-side relation in the dished member 21 and closely adjacent to the front surface thereof. Each of the heating elements 24 comprises a plurality of relatively narrow and elongated, refractory resistor-supporting members 25. Each of the mem-

bers 25 are of substantially T-shape as may be noted more particularly in Fig. 7 of the drawings. The main or body portion 26 of each of the members 25 may be substantially square 5 in cross section and is provided with two spaced lateral openings 27 and 28 therethrough. A ridge portion 29 is provided on the front surface of each of the members 25 and may be straight as illustrated in Fig. 1 of the drawings, or it may be of zigzag shape as illustrated in Figs. 5 and 7 of the drawings.

Each of the members 25 is provided with a plurality of spaced openings 31 extending laterally therethrough located partly in the main or body portion and partly in the ridge portion, as illustrated more particularly in Fig. 6, thereby forming a plurality of half-grooves in the front surface of the body portion and a plurality of intervening raised 15 portions or lateral ridges. A resistor member 32 in the form of an open helix is supported by the plurality of refractory members 25 which are located in side-by-side relation, the resistor helix extending back and forth of the assembled group of bars 25, the beginning and the end of the resistor member being located at the same end of the group 20 of bars 25.

Each set of bars 25 is mounted on and supported by a pair of metal rods 33 that extend respectively through the aligned openings 27 and 28 in the bars 25. The bars 33 are made of a metal that does not oxidize at the relatively high temperature at which the resistor member 32 operates, and I prefer to employ nickel-chrome for this purpose.

The distance of the opening 27 from the one end of the bar 25 may be made less than the distance of the other opening 28 from the other end of the bar, and by reversing each alternate bar 25 when assembling the same on the rods 33, an irregular or indented edge is obtained, substantially as illustrated in Fig. 4. If the respective heating elements comprising a plurality of bars 25, the resistor 32, and the supporting rods 33 are then located in side-by-side relation as illustrated in Fig. 4 of the drawing, the respective heating elements are interlocked or interfitted 45 relatively to each other. The amount of offset of one bar relatively to the adjacent bars is, of course, relatively small, and the upper and lower edges of the plurality of heating elements present a pleasing appearance.

It is of course understood that the zigzag portion 29 of the bars 25 is so located that the effect of a substantially continuous zigzag portion is obtained from the top edge to the bottom edge, thereby also presenting a pleasing and decorative appearance.

The heating elements 24 are supported by the rods 33 extending through suitable openings 34 in the side portions of the plate 21. In assembling the heating elements in their proper operative positions in the dished mem-

ber 21, they may first be assembled on the rods 33 in order to align the openings 31, after which the resistor 32 may be placed in its position, being threaded through the openings 31 as hereinbefore described. The bars 33 may then be temporarily removed and the group of refractory bars 25, together with the resistor 32, may be placed in substantially their proper operative position within the dished member 21, after which the rods 33 may be pushed through the side portions of the plate 21 and the openings 27 and 28. If the openings 34 are made relatively large it may be possible to assemble the heating elements by a tilting and rearward movement 80 of one end relatively to the plate 21.

A terminal construction for the heater comprises a relatively long bus bar 35 that is insulatedly mounted at one end face of the dished member 21 by any suitable means 85 such as machine screws. A plurality of relatively short bus bars 36, 37, and 38 are also mounted against the same face of the member 21 as is the bus bar 35 and in the same manner. One end of each of the resistor 90 members 32 of each heating element is connected to the bus bar 35 and the other ends are connected respectively to the bus bars 36, 37, and 38.

A terminal supporting bar or plate 39, of 95 a suitable electric-insulating material, is mounted against the front surface of the rear wall panel 18 at the same side of the casing at which the hereinbefore described bus bars are located. Terminal members 41 and 42 100 are suitably mounted thereon, the terminal 42 being connected to the bus bar 35 by a short conductor 43.

Supply circuit conductors 44 and 45 may be located in a suitable conduit 46 such as is usually provided for electric conductors in houses or other buildings. The end of the conduit 46 may extend into the casing 11 through a suitable opening in the rear panel 18, a plurality of nuts 47 (only one of which is shown in the drawing) being provided to securely hold the conduit 46 relatively to the rear panel 18. The conductor 44 is connected to the terminal 42, and the conductor 45 is connected to the terminal 41.

The casing 11 is provided with a lower front panel 48 that is suitably secured thereto by a plurality of screws 49. The panel 48 is, therefore, easily and quickly removable from its normal operative position by removing the screws or bolts 49. A metal strap 51, of substantially U-shape, is secured against the panel 48 at the inner surface thereof, and is arranged to support a plurality of control switches, 52, 53, and 54 that 115 are secured against the same by suitable bolts 55. The control switches 52, 53, and 54 are of the usual single pole snap switch type, the operating shafts thereof extending through the front panel to permit of mount- 120 125 130

ing the operating knob 56 thereof in front of the panel 48 for easy manipulation by the operator or user.

The bus bar 36 is electrically connected to the switch 52 by a conductor 57, while conductors 58 and 59 connect the bus bars 37 and 38 to the switches 53 and 54 respectively. The other terminal of the switches 52, 53, and 54 are connected together and to the terminal 41 by a conductor 61. This connection permits of energizing the heating elements either singly or together, or in any selective combination as may be desired by the user. The conductors 57, 58, 59, and 61 are made sufficiently long so that the front panel, together with the control switches operatively supported thereby, may be removed from the casing 11 to permit of an operator placing the conduit 46 and the supply circuit conductors 44 and 45 in their proper operative positions when installing the heater, or to permit of replacing the heating element in case of a burn-out.

The heater embodying my invention thus provides a plurality of extended heating elements that are located in side-by-side and interlocked positions relatively to each other in a front opening in a metal casing that is provided with a quickly removable front panel carrying the control switches for the heating elements. Each heating element comprises a plurality of relatively narrow and elongated refractory bars of electric-insulating material, each bar having an integral ridge on its front surface, the resistor helix being located partly in this ridge and partly in a groove in the front surface of the main or body portion of the bars. This construction permits of operating the resistor member at such temperature as to make it substantially radiant, and the hereinbefore described construction of resistor-supporting bars ensures a relatively low heat-storage capacity, and also ensures that a very large portion of the resistor is uncovered, thereby aiding in producing a pleasing effect when the heater is operated. The interfitting of the bars of the adjacent heating elements also aids in maintaining all of the bars in alignment, particularly so as regards those bars located in vertical alignment, where the zig-zag ridges should be properly aligned in order to produce a pleasing effect over the entire front surface of the plurality of heating elements.

While I have illustrated a specific embodiment of my invention, it is understood that such modifications as are included in the scope of the appended claims are also covered thereby.

I claim as my invention:

1. In an electric heater, in combination, a casing having an open front, a dished refractory member interlocked with said casing and located back of said front opening,

a plurality of individual heating elements supported by said refractory member, and a plurality of individual control switches for said heating elements located in said casing below said refractory member, each switch having an operating attachment extending through the front of the casing whereby the said switches may be operated separately.

2. In an electric heater, in combination, a dished member, and a heating element operatively supported by said dished member and comprising a plurality of relatively narrow and elongated refractory bars, of substantially T-shape in lateral section, mounted on spaced pairs of horizontal rods whose ends project into openings in said dished member at the side thereof.

3. In an electric heater, in combination, a casing, a dished supporting member, and a heating element located in said dished supporting member and comprising a pair of spaced rods having their ends located in said dished member and supported thereby, a plurality of relatively narrow, elongated, refractory bars located in side-by-side relation on said rods, and having a plurality of lateral openings therethrough, and an extended helically-wound resistor member extending through the aligned openings in said refractory bars.

4. In an electric heater, in combination, an electric heating element comprising a plurality of relatively narrow and elongated bars of refractory electric-insulating material located in side-by-side relation, and having an integral ridge extending in zigzag form longitudinally of said bars on the front surface thereof, each of said bars having a plurality of openings extending laterally therethrough, and a resistor member extending through the openings in said bars.

5. In an electric heater, in combination, a casing having a front opening, and a plurality of heating elements operatively supported by said casing and each comprising a plurality of relatively narrow refractory bars, each having an integral and longitudinally extending ridge on its front surface and a plurality of lateral openings therethrough, located partly in said bar and partly in said ridge portion, and an extended helically-wound resistor member traversing said openings.

6. In an electric heater, in combination, a plurality of electric heating elements, each comprising a resistor member and a plurality of relatively narrow elongated bars of refractory electric-insulating material located in side-by-side relation, and each bar having an integral ridge extending in zigzag form longitudinally thereof on its front surface, the bars of the respective elements being interfitted to maintain the zigzag ridges in substantial vertical alignment.

7. In an electric heater, in combination, a

casing and a heating element therein comprising a plurality of refractory bars, each having a ridge on its front surface and a plurality of spaced openings extending laterally therethrough and located partly in the body of the bar and partly in said ridge, and an extended helically-wound resistor member extending through said openings, the ridge portions over the openings serving to retain the resistor against forward displacement and the half holes in the body of the bar serving to position the resistor against lateral displacement.

8. In an electric heater, in combination, a plurality of individual vertically disposed and separable electric resistor supports having spaced resistor engaging devices, the longitudinal extent of each of the said supports comprising separable portions of like size and configuration, the said supports being arranged side by side and the said separable portions of each support being inverted with respect to the corresponding portions of the adjoining supports whereby said resistor engaging devices are located at different heights in adjoining supports, a plurality of resistor wires engaging the said devices, and separate control switches connected with the resistor wires whereby either wire may be caused to glow independently.

9. In an electric heater, in combination, a casing, a plurality of individual vertically disposed and separable electric resistor supports having spaced resistor engaging devices, the longitudinal extent of each of the said supports comprising separable portions of like size and configuration, each of said separable portions having correspondingly

spaced transverse openings, rods having ends borne by the casing and passing through said openings to carry said separable portions of said supports, the said supports being arranged side by side and the said separable portions of each support being inverted with respect to the corresponding portions of the adjoining supports whereby said resistor engaging devices are located at different heights in adjoining supports, a plurality of resistor wires engaging the said devices, and separate control switches connected with the resistor wires whereby either wire may be caused to glow independently. 40 45 50

10. In an electric heater, in combination, a casing, a plurality of individual vertically disposed and separable electric resistor supports, the longitudinal extent of each of said supports comprising separable portions of like size and configuration, means borne by the casing for carrying the said separable portions in vertical alignment, each of said 55 60 65 portions having at the front a series of spaced passages, the said supports being arranged side by side and the said separable portions of each support being inverted with respect to the corresponding portions of adjoining supports whereby the said passages are located at different heights in adjoining supports, a plurality of resistor wires passing through the said passages in said portions, and separate control switches connected with 70 the resistor wires whereby either wire may be caused to glow independently.

In testimony whereof, I have hereunto subscribed my name this 14th day of September 1923.

JULIUS F. ADAMS.
